COLLAR OR THE LIKE AND METHOD OF
MANUFACTURING THE SAME

Howard C. Underwood, New York, N. Y.

Application October 20, 1934, Serial No. 749,190

4 Claims. (Cl. 2—131)

Among the principal objects which the present invention has in view are: To manufacture collars having the material thereof woven as of a heavy integral thickness, such as of multi-ply fabric; to produce a collar or the like for permanent or detachable to the wearing apparel, such as a shirt; to prevent the unraveling of the threads comprising the fabric along the hem edges; to produce the material providing the top edge with a pinked or notched edge; to produce the forward thrust or throat portion of the collar or the like with a similar pinked or notched edge; to avoid bulging or uneven appearance at the corner points of the collar; to provide an enlarged notch or cut-out portion in the hem adjacent said corner points to allow take-up in the material when forming the hem edges; to present a collar for attachment to a shirt having perfect corner point construction; and to obtain other advantages and results as may be brought out in the following description.

Drawing

Figure 1 is a face view of a blank strip of material from which a collar or the like is cut, the outline of the collar being shown in broken lines;

Figure 2 is a face view of the collar blank shown as cut from the strip of material;

Figures 3, 4, 5 and 6 are similar views of one corner of the collar and showing the successive steps utilized in carrying out forming the collar.

Description

As seen in the drawing, the reference numeral 10 indicates a strip of appropriate material, the body portion 11 of which is shown as a woven material of a heavy integral thickness, preferably a multi-ply fabric having a selvage at least at the edge at the bottom of the collar. Referring to Figure 1, it will be understood that the first operation in collar making is cutting the collar blank from the strip of material 10 whereon is shown in broken lines the outline of a collar. Said collar blank may be cut from the material by suitable means (not shown) which is more specifically shown and described in my co-pending application Serial No. 752,192 filed November 9, 1934. The present disclosure is furthermore an improvement over the method shown in Patent No. 1,934,154 issued to me November 7, 1933.

In cutting the collar blank 12 from the strip of material 10, the lowermost part of the blank at the corners preferably includes the selvage of the

material and between those lowermost corners, the material is cut on an arc inwardly of the selvage. Heretofore, in cutting collar blanks from the material it has usually been done with a straight edge cutter, and in so doing the threads comprising the woven material have unraveled thereby causing considerable wastage of material. According to the present invention, the collar blank 12 when cut from the material is preferably provided at its longitudinal lower 10 arcuate part with a pinked edge or V-shaped notches 13 extending from adjacent the one end or selvage part of the corner to adjacent the other end. In the present disclosure the pinked or V-shaped notched edge interrupts or prevents any 15 possibility of the threads deleteriously unraveling, thereby assuring the forming and preservation of a perfect hem, without wastage of material, also, assisting in the application of the binding and stitching the same thereto.

It will be noted that the pinked edge runs parallel to an indicated broken line 14, said broken line representing the fold line for creating the hem. At the outer ends of said broken or fold line 14 and on either side of the collar 25 blank 12 the blank is cut to obtain an acute point 15 which includes the selvage 16 of the blank. The transverse edges of the collar blank likewise may be provided with a pinked edge 17, and in this instance the pinking does not occur 30 along the full or entire edge, but begins next the point and extends part-way along said edge. Towards the acute point 15 and in the transverse pinked edge, it will be observed that the blank is provided with an enlarged V-shaped notch 35 18 substantially the depth of the hem, the purpose of which will be hereinafter more fully described. It further will be noted that a fold line 19 is indicated as extending upwardly at an angle from the extreme outer ends of the fold 40 line 14 to the outside corner of the first notch of the pinked edge 17.

As seen in Figure 3, the first step is to fold the longitudinal hem edge along the fold line 45 14, and then the material comprising the acute point 15 may be folded substantially simultaneously on the fold line 19, said corner resting on and overlying the end of the longitudinal hem edge. It will be noted that owing to the angle of the fold line 19 the acute point substantially 50 meets the outside point of one notch of the longitudinal pinked edge 13. Creasing and folding the hem and the corner point is effected in any suitable manner.

The next step, as illustrated in Figures 4 and 5 55

is to complete the folding of the unfolded portion of the end hems on the fold line 20 of Figure 3. In making this final fold, it will be observed that the folds meet at the corner thereby obtaining a perfect point 21. In carrying out this fold the selvage 16 comprising the corner point 15 is folded upon itself thereby obtaining reinforcement for the corner, which during laundering operations will withstand the usual rough handling and so forth. As will further be seen in Figure 4, the end hem after having been folded, particularly the part comprising the corner will have a tendency of protruding or meeting the fold line 14, which in practice is disadvantageous. To overcome this disadvantage of the hem protruding over the fold line 14, I now refer more particularly to the large notch 18 shown in Figure 5. During the folding operation through mechanical folding means, the material comprising the hem is pushed slightly towards the said notch thereby closing the gap existing between one side wall of the notch and the other side wall. In other words, the spread of the notch is somewhat lessened simultaneously with the pushing of the material, heat is then applied which prevents the material from again spreading at the notch.

Upon completion of the folds, as indicated, a strip of tape 22 or other suitable material is then applied entirely around the hem and rows of stitches 23 are applied and the collar completed as shown in Figure 6.

I claim:

1. A method of manufacturing collars and the like comprising cutting a blank for providing a hem at two sides intersecting to make a corner, making a notch inwardly of the edge of one hem

adjacent said corner, and folding the hems, contracting the notch and withdrawing the end of said notched hem back of the folded edge of the other hem.

2. A collar and the like comprising a body portion having a longitudinal and transverse hems with straight folded edges meeting at a corner, one of said hems intersecting the other hem at said corner, the first said hem having a notch slightly back from its end enabling said end to be pressed inwardly toward said notch without disturbing the straight edges at the folds of the hems.

3. A collar and the like comprising a body portion having a longitudinal and transverse hems with straight folded edges meeting at a corner, one of said hems intersecting the other hem at said corner, the other hem having a notch slightly back from the folded edge and slightly spaced from its end with the portion of the material from said end to the notch pressed inwardly toward the notch and back from the folded edge of the first said hem.

4. A collar and the like having a longitudinal and transverse hems each provided with straight folded edges and meeting at a corner, said longitudinal hem intersecting the transverse hem at said corner, each of said hems having a plurality of V-shaped notches with the transverse hem having an enlarged notch slightly spaced back from the end at the corner, one wall of said enlarged notch being pressed inwardly toward the other wall and back from the folded edge of the longitudinal hem whereby the said transverse hem with the enlarged notch will not overlap the folded edge of said longitudinal hem.

HOWARD C. UNDERWOOD.
